UNITED STATES PATENT OFFICE.

CASPAR JAGY AND FREDERICK DENZLER, OF NEW YORK, N. Y., ASSIGNORS
TO WALTER K. MARVIN, OF SAME PLACE.

IMPROVEMENT IN LOCKS.

Specification forming part of Letters Patent No. 41,817, dated March 1, 1864.

To all whom it may concern:

Be it known that we, CASPAR JAGY and FREDERICK DENZLER, both of the city, county, and State of New York, have invented a new and Improved Burglar-Proof Lock; and we do hereby declare that the following is a full, clear, and exact description of the same, reference being had to the accompanying drawings, making a part of this specification, in which—

Figure 1 is an internal view of our invention; Fig. 2, a transverse vertical section of the same, taken in the line *xx*, Fig. 1; Fig. 3, a horizontal section of the same, taken in the line *yy*, Fig. 1.

Similar letters of reference indicate corresponding parts in the several figures.

This invention relates to an improved lock of that class which are provided with tumblers operated through the medium of a key, and the bolt moved by a separate or distinct application of power, and commonly termed "burglar-proof locks."

The object of the within-described invention is to simplify the construction and arrangement of this class of locks so that it will not be necessary to employ both hands simultaneously in unlocking and locking the lock, and the lock rendered incapable of being picked by tampering with the tumblers while in either a locked or unlocked state.

To enable those skilled in the art to fully understand and construct my invention, I will proceed to describe it.

A represents the case of the lock, which may be of rectangular form; and *B* is the bolt, arranged in the usual way, so as to slide longitudinally in the case *A*. The bolt has a short bar, *C*, projecting horizontally from it, as shown in Figs. 1 and 3.

D represents a swinging plate, one end of which is fitted loosely on a pin, *E*, in the case *A*, the plate being allowed to work freely on the pin. The plate *D* at its outer end—that is to say, the end opposite to the one where the plate is fitted on the pin *E*—has an opening in it, the edges of which have three distinct curves, *a b' c*, as shown clearly in Fig. 1. The upper curve, *a*, is a part of a circle quite large in diameter. The curves *b' c*, which are at the ends of *a*, are parts of quite small circles, and the curve *c*, which is at the

lower part of the opening, is a part of a circle considerably larger than those of the curves *b b'*, but not so large as that of the curve *a*. In this opening of the plate *D* an arm, *F*, which projects from the knob-arbor *G*, works, said arm having a friction-roller, *d*, in its outer end, which acts against the curved surfaces *a b b'* of the opening in the plate *D*. The arm *F* has a projection, *e*, which extends through the opening in the plate *D*, and acts against the edge of an opening, *G'*, in the bolt *B*, for the purpose of sliding or shooting the latter back and forth to lock and unlock the lock.

In order to avoid confusion, we will proceed to describe the operation of the knob-arbor upon the bolt *B* and swinging plate *D*, before giving a description of the other parts of the lock.

When the bolt is in a locked state, the bolt *B* being shoved outward from the lock to the extent of its movement, as shown in black in Fig. 1, the friction-roller *d* of the arm *F* is in the curve *b* of the opening of the plate *D*, and the latter is depressed or forced down to the extent of said movement by a spring, *H*, which is attached to the plate *D* and bears against the upper part of the lock-case. (See Fig. 1.) The short bar *C* on the bolt *B* serves as a stop for the plate *D*, determining the extent of its downward movement, the bar *C* passing through a slot, *f*, in the plate *D*. By turning the knob-arbor *G* in a direction from left to right, as indicated by the arrow 1, Fig. 1, the roller *d* will bear against the curve *a* of the opening in the plate *D*, and throw upward or raise said plate, while the projection *e* of the arm *F* of the knob-arbor will, when the plate *D* reaches its culminating point, which occurs when the roller *d* reaches nearly the center of the curve *a*, strike against the part *g* of the opening *G'* in the bolt *B*, and throws the latter back, so as to unlock the lock, as indicated in red outline in Fig. 1. The roller *d*, in moving over the curve *a*, keeps the plate *D* in an elevated state until the bolt *B* has completed its backward movement, and at the termination of said movement of the bolt the roller *d* arrives at the curve *b'*. During the shoving out of the bolt *B*, or the locking of the lock the arbor *G* is turned from right to left, as indicated by the arrow 2, the plate *D* being elevated as before, and the

roller *d* striking against the left side, *h*, of the opening *G'* in the bolt *B*. The curve *e*, it will be seen, prevents the plate *D* interfering or coming in contact with the knob-arbor *F* while the former is being raised or elevated.

I represents a series of tumblers, which are placed on the pin *E* at about their centers, and work loosely thereon like the plate *D*. These tumblers *I* have each a spring, *i*, attached to them, said springs bearing against a pin, *j*, on the plate *D*, and having a tendency to keep the upper edges of the tumblers in contact with a stop, *j'*, attached to the plate *D*. (See Fig. 1.)

The ends of the tumblers *I*, near the opening in the plate *D*, in which the roller *d* works, are slotted longitudinally, as shown at *l*, and at the inner end of each slot *l* there is an opening, *m*. The slots *l* are sufficiently wide to admit of the bar *C* of the bolt *B* passing through them into the openings *m*, and the openings *m* are sufficiently wide to admit of the tumblers *I* working on the pin *E* to a requisite extent when the bolt *B* is shoved back and the bar *C* is within the openings *m*.

The ends of the tumblers *I*, opposite to the ends in which the slots *l* are made, are each provided with a pendant, *J*, and these pendants work in a slot, *n*, made in a bar, *K*, secured permanently in the lock-case.

The slots *l* in the tumblers *I* are in different positions when the lock is both in a locked and unlocked state, and in order to lock and unlock the lock it is necessary that the tumblers *I* be so adjusted as to bring the slots *l* in line with each other, in order to admit the short bar *C* of the bolt *B* to pass through them, and thereby allow the bolt to be moved back and forth. The adjustment of the tumblers *I* to effect this result is effected through the medium of a key, *L*, constructed by having a series of notches, *o*, made in one edge of a flat metal plate, said notches being of varying depths corresponding to the different positions of the slots *l* in the tumblers *I*. This key, when the lock is to be locked or unlocked, is fitted in the slot *n* in the bar *K*, and underneath the pendants *J* of the tumblers *I*, and when the key is thus adjusted the knob-arbor *G* is turned and the plate *D* raised, and the tumblers *I* moved so that the pendants *J* will be pressed down upon the notched edge of the key, and the tumblers thereby adjusted so as to bring their slots *l* in line with each other, and the bar *C* of the bolt *B* by the time the roller *d* acts upon the bolt to move it.

Thus it will be seen that by turning the knob arbor *G* the tumblers *I* are adjusted in

proper position to admit of the sliding of the bolt, and the bolt operated when the tumblers are properly adjusted.

When the lock is in an unlocked state, the bar *C* is within the openings *m* of the tumblers, and it is at the outer side of them when the lock is in a locked state or the bolt shoved outward.

The upper edges of the tumblers *I*, directly above the pendants *J*, bear against a stop, *M*. (Shown clearly in Fig. 1.) This stop effectively prevents the tumblers being operated upon or tampered with by instruments in order to ascertain the position of the slots *l*. This is the means usually resorted to by burglars in order to pick locks. They move the tumblers separately, and by a gentle pressure of the bolt, or some part connected therewith, against the slotted ends of the tumblers ascertain the position of the slots, and then construct a key that will suit the lock. The stop *M*, however, prevents the tumblers *I* being shoved upward, and they cannot be drawn downward, as the pendants *J* are inaccessible to any tool that would answer for that purpose.

If the plate *D* be slightly raised, so as to throw the ends of the tumblers *I* underneath the stop *M* downward sufficiently far to allow the tumblers to be moved or worked any material distance, the pendants *J* will be forced so far down into the slot *n* before the bar *C* can act upon or press against the tumblers that a tool cannot be inserted into the slot *n*.

By this arrangement the construction of burglar-proof locks is greatly simplified. There are no parts liable to get out of repair or become deranged by use, and the lock may be constructed at a very moderate cost. The key-hole also in consequence of being a quite narrow slot, does not admit of powder being introduced in sufficient quantity to blow off the lock.

Having thus described our invention, what we claim as new, and desire to secure by Letters Patent, is—

The tumblers *I*, provided with the pendants *J*, in combination with the plate *D*, bolt *B*, and knob-arbor *G*, all arranged to operate in the manner substantially as and for the purpose herein set forth.

CASPAR JAGY.
FRED. DENZLER.
